BEVERAGE DISPENSING MACHINE

Walter L. Koch, Caldwell, and Robert P. Franklin, Jefferson Township, N.J., assignors to Rowe International, Inc., Whippany, N.J.

Filed Feb. 9, 1973, Ser. No. 330,944

Term of patent 14 years

Int. Cl. D15—08

U.S. Cl. D94—3 B

FIG. 1 is a perspective view of a beverage dispensing machine from the left front thereof showing our design.

FIG. 2 is a perspective view of the beverage dispensing machine from the right rear thereof, showing our design.

We claim:

The ornamental design for a beverage dispensing machine, substantially as shown and described.
